UNITED STATES PATENT OFFICE

2,430,913

RIGHT AND LEFT HAND LOCK WITH
EXTENDIBLE KEYWAY

Americo Ciani, Mexico City, Mexico

Application January 22, 1945, Serial No. 573,886
In Mexico March 20, 1944

1 Claim. (Cl. 70—355)

1

My present invention, in its broad aspect, has reference to improvements in locks and keys therefore of the type having plural plates or tumblers which are arranged in different combinations to receive keys having removable and replaceable teeth to conform to the numbered plates of the combination whereby to operate the lock. More particularly, it is my purpose to provide a lock which may either be right-hand or left-hand operated with an extensible keyway to fit doors and the like of different widths which may be made of either wood or metal. Also, I provide a novel lock structure wherein the cover plate is attached to the casing body in a quick and effective manner, and wherein the combination of plates can be quickly and easily changed and the length of the keyway quickly and easily modified to correspond with doors of different thicknesses and the like. Furthermore, my key is practical, novel and improved and has changeable teeth to correspond with the combination of the lock thereby eliminating the hazard inherent in lost keys in the hands of an unscrupulous person.

The characteristic details of this lock and key are clearly shown in the following description, and in the drawings accompanying same by way of illustration of the said lock and key; the same reference signs serving to designate the same parts on the figures shown.

Figure 1 is a section through a door and jamb and shows my lock in place.

Figure 2 is a section on the line 2—2 of Figure 1.

Figure 3 is a section through a door and jamb and through my lock showing the tumblers and operating parts.

Figure 4 is an end view of the lock mounted on the door, with the limb on the left side.

Figure 5 is a top plan view of the lock with the arm reversed.

Figure 6 is a top plan view showing the bolt retracted.

Figure 7 is a top plan view of the lock with the lever reversed and the bolt extended.

Figure 8 is a section showing the manner of operating the tumblers.

Figure 9 is a view showing the key in place and the bolt extended.

Figure 10 is a view showing the key in place and the bolt retracted.

Figure 11 is a side view of my key.

Figure 12 is an edge view of the key partly broken away to show the manner of mounting the key teeth.

2

Figure 13 is a section on the line 13—13 of Figure 11.

Figure 14 is a section on the line 14—14 of Figure 11.

Figure 15 is a view of the tumblers showing their different forms, and

Figure 16 is a view of the key teeth showing their different forms to fit the tumblers.

My lock is provided with a case for the lock mechanism with lengthwise inner guides along which the lid slides when fastened in place with a lateral notch to enable the belt to be thrown in the manner hereinafter described: A post 2 is fixed to the bottom of the case and has a hook to hold the lid or cover in place. A cylindrical nipple 3 is fixed to the bottom of the case and has a circular central cavity to permit pivoting of the key. A hole 4 is provided to admit the spindle of the outer knob of the lock on the inside of the door, and an eccentric 5 is fixed to a disk 6 which is fastened to a conical nipple 7 fixed to spindle 8 inside the lock. An outer knob 9 is fixed to spindle 8 and is continued inside so as to turn eccentric 5. A block 10 is provided on the bottom of the case and has a screw-threaded tube 11 to hold the tumblers or plates by means of a screw head 12. Tumblers 13 of stainless metal in any quantity are provided and have numbers stamped on them progressively to designate the combinations allowable in accordance with the number thereof. The tumblers are so balanced that their operation takes place by gravity both to the right and to the left according to the side of the door on which the lock is installed. The holes 14 in the apex of the acute angle formed by the tumblers is to obtain a loose fit on tube 11, and circular gatings 15 of varying radii are in accordance with the length of the combined steps or bits of the key-teeth, with a parallel notch 16 in the radius directed towards the bolt of the lock, to admit the key. The curved projecting teeth 17 on arch 18 are to lock the tumblers when the lock is closed, and guides 19 rising from the bottom of the case are provided for lateral bars 20 of the tail of the bolt slide. Spiral springs 21 are accommodated in the case to hold the bolt in the thrown position, and an intermediate plate 23 with bottom slide projections 24 and upper catches 25 engages into notches 26 of tumblers 13. A slot 27 in intermediate plate 23 functions on either side of the bit or fixed step of each key-tooth. The lid or cover 28 protects the lock and has a lateral notch 29 which engages the hook 2 of case, and is held in place

by screws. The extensible guide bar 30 of the key operates by means of a set of disks or washers to increase or diminish its length according to the thickness of the door 31 on which lock is to be fitted and slots are provided to admit screws 32 fixing them to outer plate 33 and lid 28 of the lock, which is provided with a central keyhole 34 for the key to pass the same through plate 33, and the washers composing the guide bar 30 and lid 28.

The key is composed of two parts and a set of steps or bits in any quantity to combine them in accordance with the tumblers of the lock; the head of the key has a hole 35 to receive a key-ring; at the bottom of bar 36 a portion 37 is cut away to accommodate bits or steps 38 by means of a rectangular slot 39. At the lower end is a pin or projection 40 with a screw-thread on which to screw nut 41, which also serves as a pivot when turning the key pushed home into the lock. Below the bottom bit or step 38 is a member 42, the purpose of which is to retract the bolt, after the tumblers have been operated by the key.

The operation of lock and key is as follows: When fitted to the door either left or right hand, the first thing is to measure the thickness of the door to determine the number of disks or washers required for the keyway; they are fixed by means of screws between the outer plate and the cover of the lock, after which the lock is fastened to the cover and the screws are placed to finally attach the case of the lock to the inner part. Once installed with the combination chosen for the bits or steps of the key teeth corresponding to the tumblers of the lock, when the key is introduced into the guides the steps engage in the tumblers and turn and throw the bolt to open or shut, and inasmuch as the several steps have registered with

the tumblers, such tumblers will function by gravity.

From the foregoing, it is believed that the operation and advantages of my invention will be apparent, but it is emphasized that interpretation of its scope should only be conclusive when made in the light of the subjoined claim.

I claim:

A lock, comprising a casing formed with a body and a removable cover, the body having means forming a slide and seat for the cover, a hook, and the cover having a slot in which the hook engages, a nipple having a central cavity adapted to receive a key, the case having an opening adapted to receive the spindle of a doorknob, a bolt having laterally extending bars on the tail end thereof, on which the bolt slides, a plurality of tumblers of different form and numbered for identification, said tumblers having central slots communicating with gatings of differing radii, an intermediate plate with guide prongs engaging in the slots of the tumblers, an eccentric for drawing the bolt, and spiral springs mounted on the laterally extending bars on said bolt against which the bolt operates.

AMERICO CIANI.
